Primary Examiner—Dominic Simone(74) *Attorney, Agent, or Firm*—Marshall A. Lerner; Bradford E. Mattes; Kleinberg & Lerner, LLP(57) **CLAIM**

The ornamental design for a portion of a shoe upper, as shown and described.

DESCRIPTION

FIG. 1 is a perspective view of the portion of a shoe upper showing my new design;

FIG. 2 is a top plan view thereof;

FIG. 3 is a left side elevational view thereof;

FIG. 4 is a right side elevational view thereof; and,

FIG. 5 is a front elevational view thereof.

Broken lines in the figures are for illustrative purposes only and form no part of the claimed design.
